United States Patent Office.

HENRY D. LYMAN, OF KALAMAZOO, MICHIGAN.

Letters Patent No. 82,013, dated September 8, 1868.

IMPROVEMENT IN HORSE-SHOES.

The Schedule referred to in these Letters Patent and making part of the same.

TO WHOM IT MAY CONCERN:

Be it known that I, HENRY D. LYMAN, of Kalamazoo, in the county of Kalamazoo, and State of Michigan, have invented a new and useful Improvement in Horse-Shoes; and I do declare that the following is a true and accurate description thereof, reference being had to the accompanying drawings, and to the letters of reference marked thereon, and being a part of this specification.

Figure 1 is a perspective view, and

Figure 2 is a detached sectional view from x to x .

Like letters indicate like parts in each figure.

This invention relates to the construction of an apparatus to be attached to the ordinary horse-shoe for treating that class of disease known as contracted feet, caused by improper shoeing or otherwise, and by which many fine horses are ruined.

To enable others to manufacture and use my invention, I will now describe its construction and use.

Fig. 1 is a view of the shoe in position to be fastened to the hoof by nails or otherwise. The heels of the shoe are provided with clips B, secured and pivoted to the same by bolts C and head D, as seen in fig. 2. In the position of clips B, when upon the foot, the outside of the clips come in contact with and against the inside of the rim of the foot, and, through the aid of the pivot, adjust themselves to the angle of the hoof, and spread the same, thus producing the desired result.

What I claim as my invention, and desire to secure by Letters Patent, is—

The attachment of adjustable clips B to the heel of a horse-shoe, when operating with a pivot, substantially as set forth and shown.

H. D. LYMAN.
